UNITED STATES PATENT OFFICE.

GEORGE E. MARLATT, OF PASADENA, CALIFORNIA.

LINOTYPE-MACHINE.

1,310,487.

Specification of Letters Patent. Patented July 22, 1919.

Application filed September 21, 1915. Serial No. 52,953.

To all whom it may concern:

Be it known that I, GEORGE E. MARLATT, a citizen of the United States, residing at Pasadena, in the county of Los Angeles and 5 State of California, have invented a new and useful Improvement in Linotype-Machines, of which the following is a specification.

My invention relates to typographical machines and particularly to that type of machine known as the Mergenthaler Linotype machine as disclosed in Letters Patent of the United States No. 436,532, issued to O. Mergenthaler, and designated Model One 15 Linotype.

The primary object of my invention is to provide certain general improvements in the structure and to enlarge the scope of such machines in order that the operation there- 20 of may be greatly simplified and facilitated and the desired results accomplished with the minimum amount of attention on the part of the operator.

A further object of my invention is to 25 provide means for mixing the matrices in a line at different levels in the assembling elevator, for transferring them in such a state to, and for presenting them in the proper order at the casting position.

30 A further object is to provide an improved first elevator mechanism arranged to co-operate with the assembling elevator and transfer means for the proper handling of the mixed lines of matrices. Other objects 35 will appear in the detailed description following.

Figure 1 is a front elevation of the assembling elevator showing the division of the front assembling rails thereof into sections 40 in order to provide access to any portion of a line of matrices confined therein.

Fig. 2 is a left hand elevation of Fig. 1.

Fig. 3 is a right hand elevation of the front wall of the elevator shown in Fig. 1.

45 Fig. 4 is a sectional elevation of Fig. 1 on the line 4—4, showing one of the front rail sections in operative position and the construction of the special scale indicator.

50 Fig. 5 is a sectional elevation of Fig. 1 on the line 5—5, showing one of the rail sections in inoperative position and a rail of different design substituted therefor for the accommodation of matrices of new design.

Fig. 6 is a sectional elevation of Fig. 1 on 55 the line 6—6 of the front wall of the elevator showing the means for mixing matrices at various levels in a line.

Fig. 7 is a perspective view of a portion of the front of the machine showing the 60 rear wall of the assembling elevator, the transfer channel, matrix mixing means, and certain other improvements associated therewith.

Fig. 8 is a sectional plan of the rear wall 65 of the assembling elevator showing one of the assembling rails, the matrix mixing means and the relation of the assembler star wheel thereto.

Fig. 9 is a sectional elevation of the trans- 70 fer channel on the line 9—9, Fig. 7.

Fig. 10 is a sectional elevation of the rear wall of the assembling elevator on the line 75 10—10, Fig. 8, showing the rail operating means.

Fig. 11 is a sectional elevation of the transfer channel on the line 11—11, Fig. 7, showing the rail operating means.

Figs. 12 and 13 are sectional elevations 80 of the transfer channel on the line 9—9, Fig. 7, showing the pair of rails at different levels.

Fig. 14 is a perspective view of a portion of the front of the machine showing the assembling elevator and the transfer mech- 85 anism, and a modified means for controlling the matrices at various levels in the transfer channel.

10 Fig. 23 is an enlarged fragmentary elevation of the upper portion of the first elevator head and jaw and the vise frame in casting relation together with means for operating the matrix protecting gate.

15 Fig. 24 is a plan of the first elevator jaw and head in transfer position relative to the second elevator, showing the intermediate channel, the spaceband box, means for limiting the ascent of the elevator when recasting

20 lines, together with certain details of construction of the second elevator and intermediate channel.

Fig. 25 is an elevation of the right hand casting jaw and intermediate channel wall 25 showing the matrix protecting gate operating means.

Fig. 26 is a left hand end elevation of the intermediate channel and the second elevator in transfer relation, showing the manner of 30 transferring the matrices on their ears to the second elevator and the spacebands to the intermediate channel.

Fig. 27 is a fragmentary view in perspective of the mold disk, molds thereon, cams, 35 first elevator and vise frame showing improved means for controlling the operation of the first elevator for presenting matrices to the molds at various levels.

Fig. 28 is a front elevation of the vise 40 frame and mold disk with associated elements.

Fig. 29 is a front elevation of a portion of the front of the machine in the vicinity of the transfer mechanism showing improvements 45 of my invention associated therewith.

Fig. 30 is a sectional plan of Fig. 29 on the line 30—30.

Fig. 31 is a left hand side elevation of the lower portion of a linotype machine 50 showing my improvements thereon;

Fig. 32 is a top plan of the forward portion of the same.

In the description of the construction and operation of my improved mechanism as set forth in the specifications and drawings, 55 terms which are familiar to the trade are used to define the various parts and the operation thereof, the common and well known names of the various parts of the machine as heretofore constructed being used where 60 possible; and as a knowledge of the operation and construction of such machines is general in the trade, many of the details which are well known are not extensively 65 described except in so far as it is thought

necessary in order to properly illustrate and describe the value and relation of my improvements thereto. In order that a clear and comprehensive idea of the operation of my improvements may be had in the consideration of this invention I will show in the drawings and describe in the specification the intimate connections between the assembling elevator, the transfer channel and the first elevator, and the means for mixing 70 the matrices in the line in all of these elements, but inasmuch as the operation of the unrelated elements in a machine of this character will be readily understood by those skilled in the art, views of the complete machine are omitted from the drawings.

The several elements of a typographical machine arrangement described are intended to accommodate matrices of several different 85 designs; and in addition to having distributing teeth combinations on each end and character cavities on opposite edges, the matrices are provided with ears of various length depending upon the number of character cavities of a given size which are permissible by the established length of the matrices. For instance, in Fig. 17 matrices are shown which have full length ears on each end and two character cavities on each 90 edge; in Fig. 19 matrices are shown having full-length ears on one end and half-length ears on the other end and three character 95 cavities on each edge; in Fig. 20 matrices are shown having full-length ears on both ends 100 and four character cavities on each edge; and in Fig. 18 matrices are shown having two pairs of full-length ears and one large character cavity on each edge.

A matrix provided with half-length ears 105 on both ends will accommodate character cavities of still larger dimension than shown in Fig. 18. In order to render matrices of these several designs available for use and for the purpose of mixing the multiple characters on their edges at various levels in a line for placing characters of different design on a common level relative to the mold cell, a special form of assembling elevator is provided together with certain improvements 110 in the intermediate channel, the first elevator jaw and the mold. The new form of construction of the assembling elevator is shown in Figs. 1 to 8 inclusive and Fig. 10 and will first be described.

Heretofore the assembling elevator 360, which is commonly known in the art, has been provided with one stationary rail and one movable rail positioned in the front wall thereof for assembling matrices at two different levels, either in mixed lines or otherwise. In the present invention the rear wall 361 of the elevator is provided with the usual stationary rail 362 and the movable rails 363, 363' and 363'', any desired one of which may 125

be extended forward of the wall 361 for supporting the matrices or withdrawn from the matrix line to a position within the wall, at will. The rails 363, 363' and 363'' are adapted to be manually operated by means of crank pins 364, 364' and 364'' which are pivotally mounted in the rear wall 361 and are provided with handles 365, 365' and 365'' which are secured to the upper ends of the pins and rest on the top of the wall. Eccentric cranks 366, 366' and 366'' are formed on the lower ends of the pins and engage suitable slots in the rails with which they are respectively associated, so that by turning the handles on the pins, the movement of the rails in and out of the rear wall of the elevator may be effected.

Each of the movable rails 363, 363' and 363'' has a pin 368, 368' or 368'', as the case may be, which is secured in and depends from the rail and to which one end of the springs 369, 369' and 369'', respectively are secured at one end, the other ends of the springs being secured to pins 370, 370' and 370'' on the outside of the cover plate 371 of the rear wall, and the springs being inserted in suitable recesses or bores 372, 372' and 372'' in the rear wall. These springs normally hold the rails within the wall and the movement thereof outwardly from the wall into the matrix channel is effected by means of the crank pins, which, when turned by means of the handles thereon moves the eccentric portions 366, 366' and 366'' from engagement with the inner edges of the slots 367 and the outward movement of the rails into the matrix channel is limited by means of the pins 373 and 373' secured in the rear wall 361 which engage slots 374 and 374' in the rails, as shown in Fig. 8.

The independent movement of each of the rails is effected by means of slots 375 which are provided in the two upper rails 363 and 363' through which the crank pins extend, the lower rail crank pin 364'' extending through the slots in the rails 363 and 363' and the central rail crank pin 364' through the upper rail 363.

Matrices may be mixed at the several levels on the single stationary and the three movable rails by means of the vertical, pivoted shaft 376 carrying a handle 376' above the top plate 376'' and provided with sectors 377, 377' and 377'' secured thereto at the levels of the movable rails 363, 363' and 363'', as shown in Fig. 7. One of the edges of each of the several sectors is in the same vertical plane with the corresponding edges of the other sectors; the upper sector 377 is of approximately 90 degrees in extent, the central sector 377' about 180 degrees, the lower sector 377'' about 270 degrees, and the remaining 90 degrees of the complete circle not embraced by the sectors provides a clearance through which the matrices may pass

to the lowest, or fixed rail 362, all of the sectors being movable in the circular recesses 378 in the ends of the rails 363, 363' and 363''.

Matrices may be assembled on the upper rail 363 by turning the vertical shaft 376 so as to move the sector 377 to the position shown in Fig. 7 where it will obstruct the incoming matrices and close a break 379 in the forward edge of the upper rail 363 which communicates with the recess 378. Likewise, matrices may be assembled on the central rail 363' by turning the shaft 376 so that the upper sector 377 will assume a position within the recess 378 and the central sector 377' will be exposed through the recess 378 in its associated rail 363' so as to obstruct the incoming matrices. In a similar manner matrices may be assembled on the lower rail 363'' by turning the shaft 376 so that the sectors 377 and 377' will be entirely within the recess 378 in their respective rails 363 and 363' and the sector 377'' will be exposed through its recess 378 and will obstruct the incoming matrices. When matrices are to be assembled on the stationary rail 362 the shaft 376 is turned so that all of the sectors 377, 377' and 377'' are within the recesses 378 in the rails 363, 363' and 363'' so that the matrices may pass thereby and assume a position on the lower rail 362. The position of the vertical shaft 376 is identical with that of the usual trip wire 380 which serves to release the transfer carriage, and this shaft is therefore adapted to receive and hold this wire rigidly above the handle 376'. A single matrix may be raised from a lower to an upper position in the channel by raising the shaft 376 without turning it.

Figs. 1 to 6, inclusive show auxiliary means for mixing the matrices, said means being mounted on the front wall 382 of the elevator and is adapted to be associated with the means on the rear wall just described. This form of mixing means includes a vertically movable plate 383 which has ribs 384 formed on its inner surface and is provided with a suitable knob 385 by means of which it may be raised to a desired position. The plate 383 is adapted to be held in a selected position by means of a spring 387 which is bent to engage grooves 388 in the outer surface of the plate and is held in place against the wall by means of a rod 389 which extends in front thereof.

The plate 383 may be moved vertically for placing the upper rib 384 on its inner side in horizontal alignment with any one of the four rails on the rear wall 361, and when assembling a line of matrices, the use of this plate is preferable to the rear matrix mixing means until the line is nearly assembled, when the latter may be used for controlling

the level of the final matrices in the line. This is the primary purpose of the rear matrix mixing means, as the extended edges of the sectors 377, 377' and 377'' are much 5 narrower than the ribs 384 on the plate 383.

The ribs 391 on the front wall 382 of the elevator are in the same horizontal planes with the rails 363, 363' and 363'', but are of different form. The front wall of the 10 elevator is subdivided into a plurality of narrow sections 390 which are mounted pivotally on the horizontally disposed shaft 389 journaled in bearings 392 and 392' at opposite ends of the elevator on brackets 393 15 and 393', respectively, the brackets being secured to the face of the elevator by means of screws 394 and 394'. The sections 390 are held normally in vertical position by means of a comb-spring 395 with the teeth 20 395' of the spring opposite and resiliently engaging each of the sections and secured to the face of the elevator by means of screws 397. A shoulder 398 is formed on each of the sections 390 which is adapted 25 to be engaged by the resilient teeth 395' of the spring 395 and the sections are thus held resiliently in position on the elevator.

Ready access may be had to any portion 30 of a line of matrices by means of the yieldable sections 390 for changing a single word or character, as for instance, from one to another level, or for removing a wrongly-assembled matrix and substituting a correct character therefor, in such event, one or more 35 of the sections being turned outwardly together with the matrices resting thereon, and the correction or change made. In addition to their being individually held in their vertical position by the spring 395, the sections 40 are held in serial alinement by means of a rib 399 which is common to all of the sections and is either formed on or secured to the shaft 389. This rib engages and extends 45 through the radially formed slots 400 in the sections, as shown in Figs. 4 and 5, and its engagement with the lower end of the slots in the sections serves to hold the latter in their vertical position. The left hand end of the shaft 389 has a crank extension 50 401 which extends outwardly from the elevator where it is connected with one end of a spring 402 which is held at its other end on a screw 403 secured in the bracket 393 on the front wall of the elevator and this 55 spring serves to hold the rib 399 on the shaft in resilient engagement with the end of the slot 400 in the sections 390.

Matrices having full-length ears may be 60 assembled on a single supporting rib 404 on the plate 405 which is provided as a substitute for the three upper ribs on the front wall, and to accomplish this it is necessary to turn the sections 390 downwardly, as shown in Fig. 5, and insert the plate 405 be- 65 tween the front wall of the elevator and the

sections, the sections 390 being flattened at a point 406 opposite the shaft 389 to accommodate the plate.

The gate 407, as shown, is of somewhat different form than that usually employed in this class of machines and is provided with arms 408 and 408' at opposite ends thereof which are mounted together with the sections 390 on the shaft 389. The gate is held in its normally vertical position by means of a spring 409 which is secured at opposite ends, respectively, to a pin 410 on the arm 408' and a screw 411 secured in the front wall of the elevator and extending through the bracket 393, the spring being so arranged that the pull thereof will be in a plane to the rear of the center of the shaft 389.

The upper rail 412 of the gate has beveled edges in order that the graduations thereon 35 which represent units in length may closely approach the matrix line, while the central face of the rail is flat and has a scale in "ems", represented by numerals thereon 40 which correspond to the graduation lines on the edges. The rear side of the rail is parallel to the forward central face which extends outwardly for a sufficient distance from the beveled edges to provide grooves for receiving the inwardly turned 45 edges 413 of an index slide 414 which has a plurality of centrally positioned openings 415 through which the numerals on the scale may be observed and the index is also provided with graduations corresponding to those on the scale and which are numbered in reverse directions on opposite edges.

When the left hand end of the index slide 155 is used to indicate the length of a full line 155 of matrices, the numerals and graduations on the upper edge will indicate the remaining space in an unfinished line, and the graduations on the lower edge thereof serve to assist the operator in centering the central 140 group of matrices in lines having words of varying length in the center and at each end of the line. This latter result is accomplished by omitting the central group of characters until the other characters in the 145 line are assembled, then assembling the central group last, determining the measurement from the right hand end of the scale 150 on the rail 412, dividing the result and opening up the matrix line at a point indicated on the lower edge of the index slide 414, which is equal to half of the length of the central 155 group of characters. The index slide, for this purpose, is set so that its right hand end indicates one half of the entire length of the line being assembled, and the central group of matrices is inserted where the line is opened and is thus centered relative to the entire length of the line.

For the purpose of preventing the vertical 160

displacement of the matrices after the line has been assembled and the elevator raised toward and to the top of its runway, such as might occur for instance, when the substitute rib 404 on the plate 405 is in use and all of the rear wall rails are withdrawn from the matrix channel, I provide means for automatically advancing one or more of the rear rails so as to cover the lower ears of the matrices when the elevator is raised, thus insuring the proper alignment of the matrices for transfer to the intermediate channel. This means is shown in Figs. 7 and 8 and provides for the operation of only one of the rails for the purpose stated, but each of the rails may be similarly operated by like means. The device consists of a vertically disposed operating bar 416 which is secured to a suitable member 417 of the matrix frame at the rear of the assembling elevator and the front side of which projects into the path of an extension 418 on the rear edge of the rail 363 which operates through an opening 419 in the rear plate 371.

The initial movement of the elevator engages the extension 418 with the beveled surface 420 on the lower portion of the bar 416 and forces the rail 363 forward in opposition to the tension of the spring 369, thus locking the matrix line against displacement by jar or otherwise, when the elevator reaches the top of its runway. The lowering of the elevator disengages the extension 418 from the beveled surface 420 of the bar and the spring 369 withdraws the rail 363 from the matrix channel.

A modified means for locking the matrices against displacement is shown in Figs. 14 and 15, and this form of device is applicable to the usual form of assembling elevators. This modified means includes the usual horizontal shaft 421 which carries levers 422, 422' and 422'' for controlling the operation of the duplex rail sections 423 and 423'. The shaft is journaled in bearings 424 and 424' on the front wall of the elevator and an additional lever 425 is secured to the left hand end thereof by means of a suitable set screw 426 and has arms 427, 427' and 427'' formed thereon. The duplex rail levers 422, 422' and 422'' have split hubs and cling to the shaft with sufficient friction to render them movable with and by the shaft or independently thereof.

The levers 422 and 422' are rigidly connected by means of a rod 428 which may be used to manually control the duplex rail section 423. A bracket 429 is adjustably held on the lower edge of the intermediate channel member 430 by means of a screw 431 extending through a slot 432 therein. The lower rib 429' of the slide bracket 429 extends rearwardly under the channel member 430 for the purpose of guiding it thereon, and this slide, when moved to a position at

the right of the member 430, as shown in Fig. 14, is in alignment with and adapted to be engaged by both the upper arm 427 and the lower outer arm 427' on the lever 425 during the movement of the elevator. Above the bracket and in the path of the lower arm 427', a rail 433 is secured to the channel member 430 in a vertical position by means of screws 434.

During the upward movement of the elevator, when the slide bracket is in the position indicated, the curved extension 435 of the slide will be engaged by both of the arms 427 and 427' and the vertical rail 433 will be engaged only by the arm 427'. But, when the slide is moved to the left the upper arm 427 will engage the flat surface of the channel frame 430 and the arm 427' will engage the extended portion 435 of the slide and the rail 433 when the elevator is raised.

It is intended that the slide 429 should be moved to the left and out of the path of the upper arm 427 when matrices are being assembled continuously on the duplex rails 423 and 423', thus insuring the retention of the rail sections in operative position regardless of the successive movements of the elevator. However, in the event that it may be desired to insert the rails 423 and 423' merely for the purpose of locking the matrices as the elevator is raised and to withdraw them when the elevator descends, then the bracket may be moved to the right.

With the bracket in position at the right hand extreme of its movement, the elevator being in its lowermost position and the rails withdrawn from the matrix channel, the arm 427 is immovably held in one direction by the extended portion 435 of the slide bracket 429, and in the opposite direction by means of the engagement of the inner arm 427'' with the front surface of the elevator.

The ascent of the elevator engages the lower arm 427' with the extended portion 435 of the slide, the shaft 421 is turned in its bearings thereby, the rails are moved into the matrix channel, and the upper arm 427 is moved inwardly a corresponding distance. While the elevator is in its uppermost position the arm 427' is maintained in its outermost position by its engagement with the vertical rail 433; and when the elevator is again lowered the duplex rails are again withdrawn from the matrix channel by means of the engagement of the arm 427 with the bracket extension 435.

A single or limited number of lines may be assembled on the duplex rails by moving the rails into the matrix channel without moving the bracket slide 429 to the left; in which case the ascent of the elevator turns the shaft 421 in the hubs of the levers 422, 422' and 422'' and leaves the levers in such a relation to the shaft as to effect the withdrawal of the rails in the usual manner.

when the elevator again descends. The operation of these rails either mechanically or manually applies to either the short or the long section, or to both sections in unison.

5 It is intended that the lowermost or stationary rails in the assembling elevator should be used only when assembling matrices having full-length ears, as matrices of all other designs are assembled on the 10 three movable rails in the rear wall of the elevator. Matrices having full-length lower ears are transferred from the assembling elevator to the intermediate channel on the lower ribs 436 therein, if at their lower level, 15 and on their upper ribs 437, if at their uppermost level. In order to effect the transfer of such matrices at their lower level it is necessary to withdraw the central rails 20 438 which are movably held in opposite sides 439 of the channel frame, the movement of these rails being performed in a manner similar to that employed in the rear wall 25 of the elevator, by means of vertical crank pins 439' having handles 440 at their upper ends and cranks 441 at their lower ends 30 which engage and operate in apertures 442 in the rails 438.

35 Matrices which may be assembled on the lower ribs 436 are prevented from vertical displacement by means of the upper and central ribs 437 and 438 which extend inwardly over the lower ears of the matrices. Matrices transferred on the upper ribs 437 are prevented from vertical displacement by 40 ribs 443 which project over the upper ends of the matrices. It is preferable in effecting the transfer of the matrix lines through the intermediate channel to support the matrices by their upper ears in order to avoid 45 wear on the lower ears as the wear results in an improper face alignment when the matrices are locked against the mold in the casting operation. The repeated dropping of the matrices into the assembler causes the 50 lower ears thereof to wear excessively and out of proportion to the wear on the upper ears. Only those matrices which occupy the lowest position in the line of mixed matrices may be thus supported on their upper 55 ears, but all matrices which may be assembled at a uniform level may be supported on the upper ears by means of the rails 444 which are about centrally positioned between the upper and lower edges of the 60 channel, and which correspond to the rails hereinbefore described for a similar purpose, except that they are vertically adjustable so that they may register with the three separate levels at which the matrices may be assembled and transferred.

65 The adjusting means for the rails 444 as shown in Figs. 7, 12 and 13, consists of the compound levers 445 and 446 which are pivotally mounted on opposite sides of the channel 70 on screws 447, and 448, respectively, se-

cured in the sides 439 of the channel. The adjacent ends 445' and 446', respectively, of the levers 445 and 446 are pivotally connected by means of a disk-socket joint disclosed in Fig. 7. The left hand ends of the 75 levers 445 have inwardly extending pins 449 which operate through slots 450 in the walls 439 of the channel, and the inner ends of the pins engage the left hand ends of the rails 444. The opposite rails 444 and both 80 of the sets of operating levers are connected and adapted to operate in unison by means of a yoke 451, the upper ends 452 of which are pivotally connected with the levers 446 and the right hand ends of the rails 444, 85 the lower central portion of the yoke passing around and beneath the bottom of the channel 430.

90 The inner ends of the pins 449 co-act with the yoke ends 452 for moving opposite ends 95 on both the front and rear rails 444 in unison when the compound levers are operated, and a vertical movement of the yoke moves the rails a corresponding distance vertically. A pair of co-acting and commonly pivoted grips 99 100 105 453 are mounted on a pin 454 in the central lower portion of the yoke 451 midway of and just below the bottom 433 of the channel 430. The ends 456 of these grips serve as 110 handles for effecting their operation and their upper ends 457 engage longitudinal 115 grooves 458 oppositely formed on the sides 439 of the channel. One of the grooves on each of the sides is provided for each of the three levels at which matrices may be suspended in the channel and the movement of the grips from one to the other of the pairs of grooves moves the rails 444 correspondingly, and the rails may be thus held in 120 position until it becomes necessary to change 125 them.

A modified form of the device just described is shown in Figs. 14 and 15 and is intended for use in connection with the duplex matrix system heretofore employed in 110 this class of machines. This form of device is specially adapted for use with matrices having half-length ears, and the right hand end only of the rails 444 are movable for the purpose of alignment with the lower sides 115 of the upper ears of the matrices when they are in transfer position in the assembling elevator. The left hand ends of the rails 444 are pivoted on screws 459 in the inner sides of the channel 430 and are held in their usual position so that matrices having half-length upper ears may be transferred to the casting jaw at one level, and those having full-length ears may be transferred at a different level. When the matrices are assembled at the upper level in the assembling 120 elevator, they are supported on their lower ears in the intermediate channel in the usual manner, and the rails 444 retain their lower position; but when they are assembled at the 125 130

lower level their upper ears engage the rails 444 and in the event that the upper ears are of half length the right hand ends of the rails 444 must be raised so as to support the 5 matrices immediately when they leave the assembling elevator. The movable ends of the rails are connected with the yoke 451 and are adapted to be operated thereby in a manner similar to that described in connection with the form shown in Fig. 7.

The first elevator jaw into which the matrix lines are carried from the intermediate channel, and are lowered thereby to the casting position, is of a different form 15 from that commonly employed in type casting machines and is intended to present any of the characters on the several designs of matrices, which will be hereinafter described, to the mold for casting slugs therefrom. This jaw has self-contained means 20 for raising the matrices from their several levels therein to a common upper level prior to their transfer to the second elevator, and is also provided with means for depressing 25 the ears of the spacebands into a position below the upper ears of the matrices when they are at their common upper level.

In addition to its being provided with 30 ribs for permitting the mixing of matrices at as many levels therein, the jaw is also associated with means for limiting its descent at three different levels in front of the mold, for the purpose of presenting any selected character cavity on the edge of the 35 several styles of matrices to the mold slot for receiving the cast of metal. The mold which is intended to be used with these other improvements is also of new and improved form and includes a face plate 462 which 40 has a plurality of parallel longitudinal grooves 463 for receiving the matrix ears of either the full-length or half-length type, and the plate is reversible on the mold in order to accommodate either of said types 45 of matrices. The grooves in the plate are adapted to receive the matrix ears at a maximum of four different levels, depending upon the distance which the casting jaw may be lowered, and to receive the matrix ears 50 at three different levels in mixed position.

The face plate 462 may also be made in several different forms in so far as the grooves 463 are concerned, and any one of the several forms of plates may be substituted for another in the mold in order to accommodate a selected type of matrix. The mold is so constructed that only those of the screws 464 which serve to hold the face plate thereon are necessarily removed 55 for the purpose of releasing the face plate therefrom, as shown in Fig. 16, thus rendering the face plate readily reversible on the mold.

The heads 465 of the screws 466 which secure 60 the mold base 467 to the mold carrier

468, extend entirely through the face plate, are secured in the mold base and their appearance on the face of the mold merely indicates a clearance in the face plate for the screw heads. It should be noted that all of the screws appearing on the face of the mold 70 are on a common line with the locking bushing 469 which is common to all line casting machine molds, and also that the sets of screws on either side of the bushing 469 are 75 placed equidistant therefrom in order to permit the reversal of the face plate 462 around the bushing as an axis.

The improvements in the mold and casting jaw are shown in Figs. 16 to 21 inclusive, the face plate 462 as shown in Fig. 16 being broken in order to show the opposite ends thereof in reversed positions on the mold. A longitudinal rib 470 is provided on the upper edge of the plate 462 for the 85 purpose of increasing the thickness of the lower lip 471 of the mold when matrices of the form shown in Fig. 19 are in use. In this figure a modified form of filling piece 472 is shown which is intended for use in lieu 90 of the rib 470 and which is clamped in position on the mold by means of the beveled edges 473 thereon and on the adjacent face plate of the modified form.

Referring to Fig. 16, it is to be observed 95 that the ribs 474 and 475 are in different positions on the face plate relative to the center of the plate, and when the plate is reversed, the distance between the upper or operating rib and the mold slot 476 is increased or diminished for the purpose of 100 registering the character cavity of a selected form of matrix with the mold slot. Other modifications of the face plate 462 are shown in Figs. 18 and 20, the grooves on one side 105 of the center in the latter view being three in number for the accommodation of three letter matrices, while the grooves on the opposite side of the center are four in number for the accommodation of four letter 110 matrices. In Figs. 17 and 18 the casting jaw is shown in its lowest position in front of the mold; in Fig. 20 it is shown in its highest position; and in Fig. 19 it is shown in a central position.

By limiting the descent of the casting jaw to lower or higher positions as shown, lower and higher character cavities on the multiple-letter matrices are presented to the mold; as for instance, the lowering of the 120 four-letter matrix to a central position in front of the casting jaw will cause the second character thereon to be presented to the mold slot, and by lowering the jaw to its lowest position, the third character will be 125 presented. In order to present the fourth character to the mold, the matrix should be assembled at a level in the assembling elevator which will permit its transfer to a position on an upper rib 477 on the multiple 130

5 rail 478, and this rib is also used when matrices are mixed at three levels, in which case the casting jaw would be lowered to either its central or lowest position, depending upon and as determined by the character selected for use.

10 The rail 478, shown in Fig. 20, which has the ribs 477 and 479 is intended for use in connection with four-letter matrices and other matrices having the usual half length lower ears and may be substituted for a rail having but one rib and adaptable to all other forms of matrices. Another form of supporting rail 480 having a single rib 481, 15 as shown in Figs. 17, 18 and 19, is reversible in position on the casting jaw for the purpose of placing the rib 481 thereon at an upper or lower level. The ribs intended for use with matrices having full-length lower ears must occupy positions at an upper level, as shown in Figs. 17 and 18, while the ribs intended for use with matrices having half-length ears must occupy lower levels, as shown in Fig. 19. Reference is 20 made to Figs. 16, 29 and 30 in addition to the views previously mentioned in order that a full disclosure of the multiple rails may be had.

25 The rail of either the form, as represented by 478 or 480, respectively, is mounted between the body 482 of the casting jaw and the plate 483 which is secured to the body 482 near opposite ends by means of screws 484, a clearance opening 485 being provided 30 in the rail through which the screws extend. The rail is held resiliently in position by means of springs 486 carried in the recesses 487, as shown in Fig. 30, which compress against the ends of the recesses 487 in 35 the rear wall 488 of the yoke member 490 on the bottom of the jaw. Diagonal slots 491 are provided in the rail which receive the arms 492 of the operating levers 493, and the movement of the arms therein moves 40 the rails from the matrix channel into the jaw body 482 against the tension of the springs 486. The front wall 494 of the yoke 490 serves as a rail for supporting the matrices at their lowest level in the jaw and 45 to raise all of the matrices to an extreme common upper level for the transfer to the second elevator. This raising of the matrices occurs subsequent to the withdrawal of the rail from the matrix channel. The 50 raising of the yoke 490 is effected by means of springs 495 which are secured at opposite ends to screws 496 in the jaw body and pins 497 extending through slots 498 in the rear wall of the yoke, respectively. The upward movement of the yoke while the rails 55 have been extended and until their entire withdrawal is prevented by means of extensions 499 on the rails 478-480 which engage the upper sides of the shoulders 500 on the rear wall of the yoke.

The yoke 490 is depressed by means of the inner and adjacent arms 501 of the levers 493 which engage the upper edge of the rear wall of the yoke. A longitudinally positioned spring 502 is secured at opposite ends 70 to spurs 503 on the central portions of the levers 493 and serves to maintain the engagement of the arms 501 of the levers 493 with the rear wall of the yoke. Vertical springs 504 are positioned in recesses 508 75 in the jaw and are secured at opposite ends to the pins 505 in the arms 506 of the levers 493 and to the screws 507 in the jaw, respectively, the combined tension of the said springs being in excess of that of the springs 80 495. The pins 505 move vertically in the slots 509 in the jaw and the said slots communicate with the recesses 508. The inner ends of the pins are secured to and supported by a vertically movable plate 510 85 which operates in a recess 511 in the jaw, and the movement of this plate effects the operation of the levers 493 for releasing or depressing the yoke 490.

90 Pins 512 are secured to the upper end of the plate 510 and are movable in the upper jaw plate 513 which is secured to the jaw by means of screws 514. These pins are depressible by their engagement with the member 515, shown in Fig. 29, with which the casting jaw engages when in its uppermost or transfer position, the member 515 being common to all type casting machines. The yoke 490, by means of its connections 95 just described and the operation of the plunger pins 512, will be operated and the matrices will be raised to a common level in readiness for their transfer to the second elevator. Guide pins 516 are provided in the recesses 508 for holding the yoke in the 100 proper position, and the lowermost position of this yoke is established by the pins 517 which are secured to the casting jaw and engage slots 518 in the yoke.

105 The action of the arms 492 against one side of the diagonal slots 491 causes the rail 480 to be retracted. There is a clearance between the arms and the inner sides of the slots to permit the reverse movement of the arms 492 prior to the restoration of the rail 110 by the springs 486, since this restoration cannot occur until the yoke 488 has been depressed by the combined tension of the springs 502 and 504, thus disengaging the yoke from lugs 499 on the rail. These same 115 lugs prevent the upward movement of the yoke until the rail has been retracted, whereupon the springs 495 raise the yoke.

120 When the matrices are mixed at three levels or are held at the highest of three levels in the first elevator, those above the second may drop to the second level when the rail 478 is retracted, as it is not essential that the matrices occupy a position above the second level in order to separate the matrix ears 125 130

from the spaceband and thin space ears as herein described. The level to which the matrices must be raised depends of course upon the position to which the spacers and spaces are depressed, and it is this level that is meant wherever a common upper level is referred to herein. Were it not for the fact that it is desirable to retain the solid ledge 9 in front of the slot 511 as a coöperating support for the matrices, the matrices could all be permitted to drop to the lowest level and the spacer and space lugs depressed a corresponding distance.

It is a matter of general knowledge with those familiar with the operation of typographical machines, that the constant transfer of the matrices on their distributing teeth from the first to the second elevator and from the latter to the distributor bar, results in objectionable wear of and injury to the distributing teeth. The transfer of the matrices on their teeth into the distributor box is merely incidental to such transfer to the second elevator and is not essential, but the transfer of the matrices on their ears rather than on their teeth has heretofore been impracticable because of the difficulty of providing means for depressing the spacebands to a position so that their ears will be below the matrix ears, as the spacebands would otherwise be transferred with the matrices to the second elevator instead of being delivered to the spaceband box. In the present invention, as shown and described, the operation of the casting jaw mechanism for raising the matrices, simultaneously depresses the spacebands so that their ears are below the upper matrix ears.

The spacebands 519, as shown in Fig. 21, are held in the oppositely formed grooves 520 in the front wall 521 and the plunger plate 510, respectively, of the casting jaw by their ears 519'. The front wall and plunger plate are secured to a spacing block 522 by screws 524 and 524', and the three members thus form a solid yoke which is depressible by the pins 512 and which is withdrawn by means of the springs 502 and 504, as previously described. The relative positions of the matrices 525 and the spacebands 519, when in transfer position, is shown in Fig. 29 in broken lines, the spacebands being supported in the laterally opposite grooves 526 in the sides of the channel 430 in a manner similar to that usually employed, as shown in Fig. 26.

The second elevator head, as shown in Figs. 24, 26 and 29 is of an improved form and consists of a block 528 having depending and inwardly turned sides 529 adapted to receive and carry the matrices 525. The sides 529 are loosely mounted on the ends of pins 530 and 536 (Fig. 29, the pin 536 being also shown in Fig. 24 as a pivot for the member 535), the pins 530 and 536 being

rigid in the block 528. The sides 529 are resiliently held against the edges of the block 528 by means of springs 531 occupying suitable clearances in the block. Opposite ends of the springs extend through clearances 8 in the sides 529 and engage pins 532 extending across the clearances through which the ends of the springs extend, the pins thus serving to maintain the tension of the springs. The pins 530 and 536 hold the sides 529 against vertical and longitudinal movement, but the sides are loosely mounted on these pins so that they may have a slight sliding motion on pins 530 and 536 against the tension of the spring 531 when the matrices enter the second elevator, the upper edges of the sides remaining in constant contact with the blocks. The pins 532 are keeper pins for the springs 531 and the springs retain the sides 529 in close engagement to the block 528 subject to the slight displacement caused by the entrance of the matrices. The second elevator link 533 is pivotally connected with the block 528 on a pin 534 in a manner similar to that usually employed with the typical form of elevator head. The block 528 has offset portions 7 extending entirely across the top edges of the transfer channel (Fig. 24) for firmly seating the second elevator head on the channel. One pair of these offsets is shown in Fig. 26 behind the keeper pins 532. A clearance (not numbered) is provided in the upper edges of the sides 529 to avoid interference between the sides and these offsets.

The springs 531 hold the sides 529 resiliently in engagement with the matrices and their tension is sufficient to hold the matrices firmly in the line while they are being delivered to the distributing mechanism. The end closing member 535 which is pivoted on a pin 536 on the block 528 coöperates with the springs 531 to hold the matrices in line, and its outer and lower end obstructs the forward movement of the matrices and is held in such relation thereto by means of a compression spring 537 which is secured in a bore 538 in the block and exerts an upward pressure on the inner end of the closing member.

When the elevator has been raised in order to permit the matrices to be transferred to the distributing mechanism, the inner spring actuated end of the member 535 engages a suitable stationary member of the distributor mechanism and the member 535 is thus removed from interference with the line and permits the matrices therein to be shifted from the second elevator to the distributor box.

It is occasionally necessary in the operation of machines of this character to re-cast a number of slugs from a single line of matrices and spacebands, in which event the transfer levers 540 and 541 (Fig. 29) must

be locked against movement, the two levers being as usual, connected and adapted to act in unison so that the locking of the spaceband lever 540 to the right also prevents the movement of the line transfer lever 541. In such an operation it is also necessary, in view of the new form of casting jaw herein provided, to limit the upward movement of the first elevator sufficiently to prevent the movement of the plunger pins 512 in order that the matrix line may be returned to casting position with the matrices at the level or levels at which they were assembled.

15 Heretofore, with the usual form of casting jaw, the locking of the first elevator for limiting its ascent was necessary only when matrices which had been assembled at the upper level were to be used for re-casting, and the elevator was locked near its bottom as a separate operation from the locking of the transfer levers. As the levers 540 and 541 must be always locked during the re-casting operation, and as the new form of casting jaw renders it necessary to always limit the ascent of the first elevator during the re-casting operation, it is therefore desirable to connect the two locking means in order to effect their simultaneous operation in unison.

16 The operative connection between the levers 540 and 541 thus rendered necessary includes a longitudinally disposed slide stop 542 which is connected by means of a link 543 to the line transfer locking arm 544 so that the latter may be moved into such a position that its end will rest over the path of the first elevator head 545, as shown in Fig. 24. The slide stop 542 has a bearing 40 in the first elevator guide rail 546 and at its other end is slidably held by means of a screw 547 on the second elevator guide post 548, a slot 549 being formed in the end of the stop to receive the screw.

45 When the locking arm 544 is raised into the position shown in broken lines in Fig. 24 so that its free end rests in front of the head of a pin 550 carried by the lever 540, the link 543 operates to advance the stop 50 542 to a position between the guide member 546 and the first elevator head, thus limiting the ascent of the elevator and preventing the operation of the plunger pins 512. The link 543 for this reason is connected to the 55 upper arm 552 of the locking arm 544 by means of a screw 553 and to the slide stop 542 by a screw 554. It is apparent that the lowering of the locking arm 544 to the vertical position shown in Fig. 29 will retract 60 the stop 542.

65 An improved form of spaceband, which is intended to be used in connection with my several other improvements, differs somewhat from the usual form and is shown in Figs. 2 and 21. The sleeve 557 has a cen-

trally formed clearance 4 for permitting the entrance of the hair space collecting finger 559 to the openings 558 in the hair spaces in the event that both spacebands and hair spaces are used in a line of matrices. A 70 smaller recess 5 communicating with the recess 4 is also provided and permits a blade 515' (Fig. 29) to engage the upper end of the spaceband wedge on which the sleeve slides and insures the dropping of the wedge 75 prior to the transfer of the spacebands to their box, a similar recess 3 being provided in the hair space 1 to receive the blade.

As the spacebands are depressed in the casting jaw to a position below the upper 80 ears of the matrices, the usual large V clearance in the spaceband sleeve is unnecessary, a stronger structure for the sleeve is permitted and a reduction of the size of the shoulder 6 is also permitted so that the 85 spacebands may be lowered to a lower level than customary in front of the mold without interference of the shoulder with the lip above the mold slot. Only enough of the shoulder is retained to properly center the 90 spacebands in the assembling elevator and elsewhere, and the shoulder 2 on the hair spaces is of corresponding size.

Inasmuch as a new form of second elevator is provided for use with my improved 95 mechanism, a new form of spaceband shifting device and means for separating thin spaces or matrices having no distributing teeth from the matrix line when they are being transferred to the second elevator, is 100 also provided, which will be presently described in detail. It has heretofore been the practice to permit hair spaces which were not intended to be delivered to the distributor, to fall into the transfer channel when the line is shifted and thence into a box 555, Fig. 29, provided for the purpose. Failure of such matrices to thus reach the box 555 results in interferences with the spacebands and prevents their proper transfer to the spaceband box 556. Thin spaces have heretofore been provided with ears 105 which conform in shape to those of the matrices.

110 It will be readily apparent that with the improved form of second elevator such matrices would be carried by their ears for transfer to the distributor box, and they are therefore provided with ears corresponding to the spaceband ears and are depressible 120 with the spacebands to a position below the second elevator head. In order that they may not be carried with the spacebands to the spaceband box they are made to extend above the spaceband sleeves 557, (Figs. 2 125 and 21) and have an opening 558, (Figs. 2 and 6) by means of which they are collected on a finger 559 carried by the spaceband lever 540. The spacebands when they are thus collected by the finger 559 may either 130

be removed therefrom prior to the next operation or stored on the finger and the latter may be raised to a non-interfering position, as shown in Fig. 29.

5 The finger 539 is mounted on a pin 550 (Figs. 24 and 29) in frictional engagement with and between a stationary sleeve 560 and a loose sleeve 561 on the pin 550, the latter sleeve being held in position by means 10 of an arm 562 and a spring 563 co-acting therewith. The frictional mounting of the finger permits it to be retained in either a raised or lowered position, at will, and the downward movement thereof is limited by 15 means of a transverse pin 564 carried by the finger, extending outwardly from each side thereof and resting at opposite ends upon the spaceband collecting arms 562 and 565. Springs 563 and 566 on the pin 550 hold the arms 562 and 565 horizontally in 20 engagement with the upper edges of the front and rear walls of the spaceband box, as shown in Fig. 24. One end of the rear spring 566 is secured to the spaceband lever 25 540 and the other to the arm 565, and one end of the front spring is held in a notch 567 on the head 568 of the pin 550 while its other end rests upon the front arm 562. These springs also serve to force the arms 30 562 and 565 against the ends of the sleeves 560 and 561, respectively, and to retain the arms in substantially parallel relation. Each of the arms has a pin 569 which 35 travels in a groove 570 formed in the upper edge of the front and rear wall of the intermediate channel as the arms are advanced for collecting the spacebands.

The spaceband lever 540 and the line transfer lever 541, as usual in the operation 40 of this class of machine, have a limited initial movement toward each other which is sufficient to shift the matrix from the first to the second elevator, and this movement is followed by an extreme movement of the 45 levers by which the end of the spaceband lever 540 and the shifting finger 571 meet at a point to the rear of the second elevator guide post 548. This second movement of the levers occurs after the matrices have 50 been raised by the second elevator from the intermediate channel and serves to shift the spacebands to the spaceband box.

The dogs 572 which are mounted on pins 573 in recesses 574 and 575 on opposite sides 55 of the upper portion of the channel walls serve to close the left hand side of the longitudinal guide channels or grooves 570 in the walls and are pivotally held in such position by means of the springs 577 in the bores 578. 60 The shift finger 571, Fig. 29 forces the spacebands into a position beyond the dogs and the grooves 570 are deflected inwardly at 579 and communicate with the intermediate channel. The advance of the lever 540 forces the pins 65 569 out of the grooves 570 and into the in-

termediate channel, thus leaving the pins in position at the rear of the spacebands or thin spaces. The dogs 572 prevent the return of the pins 569 to the guide channels 70 570, and the return movement of the lever 540 causes the pins to drag the spacebands into the spaceband box. When the lever 540 has thus returned to its extreme right hand position, the springs 563 and 566 on the pin 550 restore the arms 562 and 565 and the 75 pins 569 engage the ribs 581 on the outer walls of the spaceband box, thus leaving all of the elements in their normal position for a succeeding transfer operation.

A frequent occurrence in the operation of 80 this class of machines consists in the delivery of matrix lines which are too long to be readily received between the right and left hand casting jaws to casting position, and such an occurrence results in damage or injury 85 to those matrices adjacent to the right hand casting jaw 582. The first elevator delivers the matrices to a position between the jaws and in the event of an overset line the end matrix is forced against the jaw and is 90 caused thereby to be forced upwardly in the casting yoke 527, which action leaves the lower ear of the matrix in interference with the rib 474 of the mold and the advance of the mold disk causes the ear to be sheared 95 thereby. Figs. 22 to 25 inclusive disclose means for preventing such an occurrence and will now be described.

A spindle 583 is revolubly held in brackets 584 and 585 which are secured by means 100 of a screw or screws 586 to the elevator head 545 and the spindle has a spiral groove 587 formed thereon and carries a gate 588 at the end next to the intermediate channel. When the matrix line is lowered to a position between the casting jaws, the gate 588 is interposed between the matrix line 589 and the jaw 582, and in the event of an overset line the gate receives the impact of the casting 105 jaw and thus protects and prevents damage 110 to the end matrix of the line. When the gate is in operative position as shown in Fig. 22, a hook 590 formed thereon engages the rear wall 521 of the casting yoke 527 and thus prevents the yielding of the wall when 115 the slug is withdrawn from the matrix line after the casting operation. The gate remains closed only when the elevator head 545 is lowered to casting position and its opening and closing is regulated by means 120 of a pin 591 which is held stationary in the vise frame 592 and which engages the spiral groove 587 in the spindle 583. The spindle is of sufficient length to maintain engagement with the pin 591 when the elevator is 125 raised to its uppermost position and the groove on the spindle extends about one half a turn around the periphery thereof.

The gate is secured to the spindle 583 by means of a pin 593 and the horizontal arm 130

594 of the gate is interposed between the brackets 584 and 585, thus preventing a vertical movement of the spindle relative to the elevator head and causing the spindle to 5 move vertically therewith. When the elevator is raised a sufficient distance to disengage the gate from the casting jaw, the spiral portion of the groove is engaged by the pin 591 and the gate is caused to swing 10 outwardly into the position shown in Fig. 24.

Fig. 27 shows an improved means for controlling the descent of the second elevator to a selected one of the three levels hereinbefore referred to, the descent of the elevator having been heretofore limited at two levels by means of a suitable member which corresponds in function to the members 596 and 597 shown in the drawings. Following 15 the descent of the first elevator and the advance of the mold to engage the matrix ears, the elevator has a slight upward movement which is effected by the portion 595 of the periphery of its cam, which serves to force 20 the matrix ears into engagement with the lower side of the ribs 474 and 471 carried by the mold, and the pressure thus exerted on the matrices is intended to insure their proper face alinement relative to the mold 25 30 slot 476.

By limiting the descent of the elevator to any appreciable extent such alinement of the matrices would be interfered with for the reason that the cam roller 596 which controls the rise and fall of the elevator would be disengaged from its cam 597 at the point 35 595 on the periphery thereof which effects the alinement of the matrices. Two additional cams are therefore provided which 40 are slidably mounted on the shaft 601 in order that either of the cams 599 or 600 may engage the roller 596, or, both may be disengaged therefrom for permitting the roller 45 to engage the central cam 597.

45 The central cam 597 controls the descent of the elevator to its lowest level, the outer cam 599 to its central level and the inner cam to its highest level. The roller provided on the usual cam arm is of sufficient 50 length to engage either of the auxiliary cams 599 and 600 when they are moved longitudinally on the shaft 601 into contact with the central cam 597; but when these cams are moved into non-operative positions as 55 shown in Fig. 32, the roller will engage only the central cam. The cams 599 and 600 are connected for simultaneous movement by means of pins 602 which extend through suitable openings in the radiating arms 603 60 of the cam 597, and the cam 600 has a hub 604 with a flange 605 and is adapted to receive the end of an operating lever 606 between the flange and the cam, the movement of this lever serving to shift the cams 599 65 and 600 on the shaft 601.

The lever 606 is pivoted on a pin 607 secured in lugs 608 on the frame member 609 and its forward end has the bifurcations 610 which engage opposite sides of the vertical portion 611 of the slide bar 612 extending 70 across the face of the mold disk 468 and which is mounted on the vise frame 592. Filling pieces 613 and 614 formed of spring metal, are secured to the bar 612 in a suitable manner, their adjacent ends are bifurcated and provided with round lugs or knobs 615 and 616, and the inner and adjacent ends thereof are movable to and from opposite sides of the vertical center of the mold disk, are substantially spaced apart 80 and the knobs 615 are longer than those 616, for supporting the elevator at a correspondingly higher level.

The descent of the elevator is usually limited by the engagement of an adjusting screw 619 thereon with the vise cap 592, and a similar adjusting screw 621 depresses the vise automatic stop rod 622 which is for the purpose of stopping the operation of the machine under certain abnormal conditions. 90 The bar 612 is provided with a plurality of notches 623 on its forward edge and any one of these notches may be caused to engage a pin 624 in the vise cap, the bar being held in engagement therewith by means of a spring 95 625 which is secured to a block 626 on the vise cap, and rests yieldably against the inner edge of the bar. The engagement of the central one of the notches 623 with the pin 624 moves the knobs 615 and 616 from the 100 path of and out of possible engagement with the screws 619 and 621, thus permitting the roller 596 to engage the central cam 597 and the elevator to descend to its lowest level. The movement of the bar 612 to the 105 left so that the right hand notch therein will engage the pin 624 will cause the roller 596 to engage the outer cam 599 and permit the elevator to descend to its central level, the right hand knobs 616 and 615 being 110 moved into position between the stop rod 622 and the screw 621 and screw 619 respectively. Likewise, the movement of the bar so that the left hand notch will engage the pin 624 will cause the engagement of the 115 roller with the inner cam 600 and the elevator will be permitted to descend to its highest level in front of the mold, as determined by the thicker or left hand knobs.

Matrices are occasionally assembled on the 120 lower rails of the assembling elevator and presented at their highest level in front of the mold by means of filling members, such as are shown in Patent Number 1,099,468 for instance and corresponding in function 125 to the members 615 and 616 herein, some operators preferring to use the lower rather than the higher rails in the assembling elevator. However, if the matrices are inadvertently assembled on the upper rails and 130

are thus delivered to casting position without withdrawing the filling members, damage may ensue on account of the improper position of the matrices relative to the mold.

5 In order to prevent such an occurrence, in the event of the failure to withdraw the filling members, the bar 612 may be extended to the right sufficiently to prevent the insertion of the duplex rails 423 and 423' in

10 the assembling elevator when the first elevator is held at its uppermost level by means of the filling knobs 615 and 616. In Fig. 14 the bar 612 is shown thus extended in connection with the matrix locking means, 15 the movement of the bar to the right effecting its engagement with the slide bracket 435 and thus serving to maintain the bracket in the proper position for withdrawing the duplex rails 423 and 423'.

20 In view of the purposes set forth to lower the matrix line to an extremely low position in front of the mold it becomes necessary to limit the extent to which the spaceband driver 627 may be raised, as otherwise, damage would result to the spacebands by causing their wedges to act to a greater extent than intended and for which they are made. In order to prevent such an occurrence a filling member 628 is provided which occupies 25 a position between shoulders 629 on the spaceband driving member 630 and the lower side of the vise cap 592 when the elevator is at its lowest level. This member is secured to the slide bar 612 by means of a bent bar 631 secured at its upper end to the slide bar 612 and the lower portion of which is movable in the recess 632 in the forward side of the vise cap. The movement of the bar 612 for permitting the complete descent 30 of the elevator will also effect the movement of the filling member 628 and cause it to limit the movement of the spaceband driver, as will be readily apparent from the disclosure.

45 In view of the specially constructed molds hereinbefore described, which have ribs in varying positions, it may be found desirable to associate certain types of molds with certain levels of the first elevator. The bar 612 is therefore provided with a lower inwardly extending arm 633 which carries a pin 634 adapted to register in certain relative positions with holes 635 in the mold disk, and the holes may be provided at various positions 50 relative to the molds on the disk for the purpose set forth. The arm 633 is merely a continuation of the main portion of the bar 612 and is bent and twisted as shown; the failure to move the bar to correspond with a selected one of the molds, or vice versa, causing the pin 634 to engage the face of the mold disk when the mold advances and the engagement of the forwardly bent end 636 of the arm with the 55 vise automatic stop rod 622, thus stopping

the machine by automatic means commonly employed on machines of this character.

Having thus described my invention, what I claim as new and desire Letters Patent for, is:—

1. In a typographical machine, matrices having supporting lugs thereon, spacers having supporting lugs projecting beyond the lugs on the matrices, the first elevator yoke for presenting said matrices and spacers to a mold, rails in said yoke for supporting the matrices, other rails therein for supporting the spacers, and automatic means for moving said matrix-supporting rails and said spacer-supporting rails in opposite direction for the purpose set forth. 70

2. In a typographical machine, matrices having supporting lugs thereon, spacers having supporting lugs projecting beyond the lugs on the matrices, the first elevator yoke for presenting said matrices and spacers to a mold, rails in said yoke for supporting the matrices, other rails therein for supporting the spacers, and automatic means for depressing the spacer-supporting rails 85 for the purpose of separating the matrix lugs from the spacer lugs to permit the transfer of the matrices on their ears following the casting operation. 90

3. In a typographical machine, in combination, matrices having full-length supporting lugs, other matrices having relatively half-length supporting lugs, the assembler element having a retractable rail and a substitutional rail for accommodating matrices 100 of either lug-length, the intermediate channel for receiving the matrices from the assembler element and having therein rails retractable and insertible to correspond with the rails in the assembling element, and the 105 first elevator for receiving the matrices from the intermediate channel and having therein supporting rails for receiving the matrices at certain levels regardless of their lug-length, and a reversible single rail and substitutional duplex rail for receiving said 110 matrices at other levels depending on their lug-length.

4. In a typographical machine, in combination, matrices having upper and lower 115 supporting lugs thereon, spacers and spaces having supporting lugs projecting beyond the matrix lugs, the assembler having front and rear walls on which the spacers and spaces are assembled and supported and between which the matrices are assembled and supported; the intermediate channel for receiving the matrices, spacers and spaces in their assembled relation one to another; the first elevator for similarly receiving the matrices, spacers and spaces from the intermediate channel, means in said elevator for shifting the matrices in one direction and the spacers and spaces in an opposite direction and thus separating the upper lugs on 120 125 130

the matrices from the lugs on the spacers and spaces; the second elevator for supporting the matrices on their lugs when thus shifted, and the transfer channel for receiving the spacers and spaces.

5. In a typographical machine, in combination, matrices having supporting ears thereon, spacebands having supporting ears of greater length than said matrix ears, 10 means for assembling transferring and casting from said matrices and spacebands at more than two levels; the first elevator for moving the line to and from casting position; the elevator jaw for holding the line 15 during the movement of the elevator, and means contained within said jaw for shifting the matrices and spacebands in opposite directions in the jaw for the purpose of vertically separating their ears to permit their 20 transfer to dependent destinations.

6. In a typographical machine, the combination of means for assembling, transferring and casting from matrices at more than two levels; the first elevator for moving the 25 line to and from casting position; the jaw therefor for holding the matrices and spacebands therein; stationary spaceband storing means; and means contained within the jaw for depressing the spacebands carried there- 30 by prior to their transfer to said storing means.

7. In a typographical machine, the combination of means for assembling, transferring and casting from matrices held at two 35 or more levels; spacebands having supporting lugs thereon; the first elevator, the first elevator jaw for holding the matrices and spacebands in the elevator, rails contained within said jaw for supporting the matrices 40 and spacebands, and means for moving the matrix-supporting rails and the spaceband supporting rails in opposite directions for the purpose of vertically separating the matrix ears from the spaceband ears to permit 45 the transfer to different destinations of the matrices and the spacebands.

8. In a typographical machine, the matrices having two or more character cavities and upper and lower supporting lugs, the 50 spacers having supporting lugs extending beyond the matrix supporting lugs, thin spaces having supporting lugs conforming to the lugs on the spacers, the assembling elevator having front and rear walls on 55 which the spacers and spaces are supported at a uniform and constant level and between which the matrices are supported at various and variable levels, retractable matrix-supporting rails in the rear wall of the assembling elevator related in number to the 60 number of characters on the matrices, an element associated therewith for directing selected matrices to selected rails, a subdivided front wall having rails correspond-

ing in number and position to those on the rear wall, an element associated therewith for directing selected matrices to selected rails the intermediate channel for receiving the matrices, spacers and thin spaces from the assembling elevator and having supporting rails with those selected for use in the assembling elevator; the first elevator for receiving the matrices, spacers and spaces from the intermediate channel and having supporting rails in position corresponding 75 to any selected position of the rails in the assembling elevator and intermediate channel, means in said first elevator for automatically retracting certain of said rails and for raising the matrices on the lower- 80 most rail following the casting operation and for simultaneously lowering the spacers and thin spaces in said first elevator to position their supporting lugs below the upper supporting lugs on the matrices, the transfer channel for receiving the spacers and thin spaces from the first elevator, the spaceband lever for withdrawing the spacers and thin spaces from said channel and carrying thereon means for receiving and supporting 90 the thin spaces, and the first organ of the distributor for receiving the matrices from the first elevator, said organ having a resilient yoke for engaging the upper lugs of the matrices and thus supporting the matrices during and following their removal from the first elevator.

9. In a typographical machine, the combination of matrix assembling means, the first elevator for moving the matrices to 10 and from casting position, means for casting slugs from the matrices, and means for limiting the descent of the first elevator and extended therefrom to the assembling means for the purpose of controlling the level at 10 which the matrices may be assembled to correspond with the casting position of the first elevator.

10. In a typographical machine, in combination, the first elevator yoke for presenting a line of matrices to a mold, casting jaws between which the matrices are confined in front of the mold, an entrance closing member for said yoke automatically insertible between the matrix line and one of said casting jaws during the casting operation and automatically retractable from the yoke entrance following the casting operation, and means whereby said entrance-closing member joins the opposite walls of said yoke for the purpose of preventing the spreading of said walls with relation to each other.

11. In a typographical machine, the combination of a line of matrices; the first elevator for moving the line to and from casting position; the right and left hand casting jaw for confining the line in casting position; and means carried by the first

elevator automatically insertible between said right hand jaw and the matrix line for preventing injury to the matrices.

12. In a typographical machine, the combination of a line of matrices; the first elevator for moving the line to and from casting position; a pair of casting jaws for confining the line in casting position; means movably carried by the first elevator and insertible between the matrix line and one of said casting jaws for preventing injury to the matrices; and means for automatically operating said means.

13. In a typographical machine, the combination of the first elevator for moving the matrices to and from casting position; means for limiting the descent thereof in the casting operation; the line transfer levers for transferring the matrices; means for locking said levers against movement; and means connected with said levers for operating said elevator limiting means.

14. In a typographical machine, the combination of the assembling elevator for holding matrices at different levels; the first elevator for moving the matrices to and from casting position; the mold for casting slugs from the line; means for limiting the descent of the first elevator at different levels in front of the mold; and connecting means between the first and assembling elevators for preventing the assembling of the matrices at a level conflicting with that at which the first elevator is limited.

15. In a typographical machine, the combination of means for assembling matrices at different levels; means for moving the matrices to and from casting position; means for casting slugs therefrom; means for limiting the descent of said matrix moving means at different levels in front of the casting means; and means for inter-connecting said assembling and matrix moving means for preventing the assembling of matrices at a level conflicting with that at which said matrix moving means may be limited.

16. In a typographical machine, the combination of the first elevator for moving the matrices to and from casting position; limiting means for regulating the descent thereof at different levels; cam means co-operating therewith; and cam shifting means for connecting the elevator limiting

means with said cam means and for effecting the operating of the cams and limiting means in unison.

17. In a typographical machine, the combination of the first elevator for moving the matrix line to and from casting position; the operating cam therefor; and auxiliary cams for regulating the descent of said elevator and the operation thereof at other than the normal level in front of the mold.

18. In a typographical machine, the combination of the first elevator for moving the matrix line to and from casting position; means for moving said elevator; cam shifting and resiliently acting means for limiting the descent thereof to different levels at the casting position; and means connected with said cam shifting means for stopping the operation of the machine when said elevator is in improper relation with the casting mold.

19. In a typographical machine, the combination of the first elevator, means for limiting the descent thereof at different casting levels; spaceband driving and justification means and automatic means for regulating the extent of movement of said spaceband driving means relative to selected levels of said elevator.

20. In a typographical machine, in combination, an assembling elevator having rails for assembling matrices of multiple levels, the first elevator for preventing the matrices to a casting slot at levels corresponding to those at which they are assembled, spacebands for justifying the assembled lines of matrices, a driver for said spacebands, means for limiting the movement of said driver to correspond to the levels at which the matrices are presented to the casting slot, co-operating cam control and filler means for limiting the descent of the first elevator, and means for inter-connecting said assembling elevator rails, spaceband driver limiting means, first elevator cam control and filler means serving to prevent conflicting of all of said means.

Signed at Los Angeles, in the county of Los Angeles, and State of California, this 19th day of Aug., 1915.

GEORGE E. MARLATT.
